UNITED STATES PATENT OFFICE

CHARLES B. LONGSTRETH, OF DENVER, COLORADO

REFRIGERATOR DISPLAY CASE

Application filed September 23, 1929. Serial No. 394,446.

This invention relates to improvements in refrigerator display cases of the type employed in stores for displaying perishable goods, such as meats, dairy products, vegetables and fruits.

It is the object of this invention to produce a refrigerator display case of a simple and substantial construction, which shall be so designed that the goods contained therein will be visible to the customers from the front of the casing and in which the goods displayed shall be supported on two surfaces placed at different levels and preferably inclined with the horizontal so as to produce a double display effect that will give the customer a better opportunity of seeing and examining the goods than when the goods are all supported on a single surface.

It is another object of this invention to produce a display case of the type specified which shall be provided with a separate compartment extending the entire length of the case along the lower rear portion of the refrigerator and within which the refrigerating coils are located. This compartment is formed in part by a portion of the bottom and a portion of the rear wall and by a metal plate which cooperates with the rear wall and bottom to form the other two sides of the compartment. By means of this separate compartment, a smooth surface is provided on which the goods can be supported and which, owing to the construction which will herein-after be more fully described, can be easily kept clean. By having the refrigerating coils enclosed in a separate compartment, the moisture which is always contained within the display compartment will be kept from contact with the refrigerator pipes, and therefore the accumulation of frost on the pipes can be, to a great extent, prevented.

It is another object of this invention to provide a display case in which the usual horizontal wrapping shelf at the rear has been dispensed with so that the case can be made smaller and be constructed at a cheaper price without interfering with the desirable qualities thereof. By providing a separate compartment for the refrigerator pipes, the ordinary compartment that is usually provided

for the refrigerant can be dispensed with without decreasing the capacity of the case, all as will hereinafter become more evident as the description proceeds.

The above and other objects that may become apparent as the description proceeds, are attained by means of a construction and an arrangement of parts that will now be described in detail, and for this purpose, reference will be had to the accompanying drawing, in which the preferred embodiment has been illustrated, and in which:

Fig. 1 is a perspective view of my improved refrigerator display case;

Fig. 2 is a transverse section taken on line 2—2, Fig. 1; and

Fig. 3 is a transverse section through the refrigerator compartment showing the same in greater detail.

My improved refrigerating display case, which will now be described, has been shown as supported on a base 1 which will not be described in detail as it forms no part of my invention, except to the extent that it serves to hold the case in proper position. The display case which forms the subject of this invention consists of a bottom 2 which is preferably made from boards and a rear wall 3, which is also made from wood. A cork lining 4 is connected to the top of the bottom 2, and to the inside of the rear wall in the manner shown in Fig. 2. A bottom stile 5 rests on the front edge of the bottom 2 and extends upwardly a short distance above the upper surface of the cork lining.

A moulding 6 is secured to the inner side of the rear wall 3. A metal lining which is formed from two pieces 7 and 8 forms the inner surface of the bottom and the rear wall, and rests against the inner surface of the cork lining. The part designated by reference numeral 7

is preferably formed from galvanized sheet iron and has its front edge bent upwardly along the inner surface of stile 5 and thence outwardly along the upper surface of the stile 5 and terminates adjacent the front glass wall 9. The part designated by reference numeral 8 is preferably constructed of Monel metal and is connected with the plate 7 by means of a lock seam joint 10 and has its

upper edge connected to the moulding 6 as indicated at 11. It will be seen from an inspection of Fig. 2, that the cork insulation is thoroughly protected by the metal lining and that the insulation can therefore be kept dry so that its insulating properties will be preserved. The case is provided with end walls 12 and 13 which are preferably formed from opaque material, such as wood or metal, 5 that portion of the end walls which has been designated by numeral 14 is formed from glass. A wooden bar 15 connects the upper front corners of the walls 12 and 13 and this as well as the part 6 is provided with rabbits 16 and 17 in which the doors 18 are slidable. 10 These doors are provided with glass panels 19 in the manner shown in Fig. 2. The doors are each substantially one-half the length of the opening that they close, so that by sliding one of the doors with respect to the other access can be had to the interior of the casing. 15 A piece of plate glass 20 rests on the upper edges of the front glass plate 9 and the end plates 14 and has its rear edge resting in a rabbet 21 in the bar 15. It will be seen from the description above that the case has its walls formed to a great extent from glass so that the interior thereof will be clearly 20 visible. The rear inclined portion of the top 25 is provided with a scale shelf 22.

For the purpose of cooling the interior of this casing, a refrigerator coil, comprising pipes 23 is provided. These pipes contain some refrigerant and are usually connected 30 with an ordinary electric refrigerating machine of any approved type, or they may contain brine which is circulated through the pipes by means of a suitable pump. These pipes may be supported by means of spaced 35 supporting members 24 that are provided with openings through which the pipes pass. The refrigerating coil is located within a compartment which is formed in part by the lower portion of the lining of the rear wall 40 and the rear portion of the lining of the bottom. The other two walls of the compartment are formed from a single sheet of enameled sheet metal, which is bent so as to 45 form two sides 25 and 26, which extend at right angles to each other, but which may also make an obtuse angle as the exact angular 50 relationship is not material. The lower edge of side 25 is soldered or otherwise secured to the lining 7 at 27 and the rear edge of the upper portion 26 is secured to the lining 8 along line 28. If water tight seams or joints 55 are provided at 27 and 28, the moist air from the interior of the casing cannot enter the chamber and therefore there will be no accumulation of frost on the refrigerating coils. 60 It will be seen from the drawing that after the top and front side of the compartment have been put in place, that the entire bottom of the casing will be formed by the smooth metal surfaces of plate 7 and sides 25 and 26

and it is therefore possible to easily clean the entire bottom of the casing. Where the refrigerating coils are located within the same compartment as the goods, there is always an accumulation of moisture to the rear of and underneath the pipes which makes it very difficult to keep the case clean. 70

The upper surface of the part marked 26 serves as a support for the rack 29 and the upper surface of the front portion of the bottom supports another rack 30. These racks are forwardly and downwardly inclined and are adapted to support the meat or other material that is on display. By having the contents of the display casing on two different levels, a double display effect is produced which greatly improves the appearance of the case over what it would be if the goods were supported on a single inclined surface in the customary manner. In addition to improving the appearance of the case, it is apparent that the capacity has not been decreased over what it would be if the refrigerating coils were located in a compartment extending rearwardly beyond the rear wall 3 in the customary manner, because the upper wall of the compartment serves as a support for the article to be displayed in the manner above described. 80 85 90 95

It will be noticed that the usual wrapping shelf that is formed by the upper wall of the refrigerator compartment has been omitted in this design and the wrapping is done on the sliding doors, as this has been found just as convenient as the level surface heretofore provided. 100

From the above description it will be apparent that by providing a chamber within the display case, and by having the refrigerating coils in this chamber, a smaller display case can be used than has heretofore been thought practicable and besides decreasing the size, the construction has also been greatly simplified by the omission of the rearwardly extending refrigerator chamber. The horizontally and vertically spaced supporting surfaces give a much better display effect for reasons above pointed out. 110 115 120

The construction above described, as has previously been mentioned, makes it possible to easily clean the inner surface of the case so that it can be readily kept in a sanitary condition. 125

From the above description it will be apparent that I have produced a refrigerator display case which possesses several marked advantages over the ordinary type of case, and which by the simple expedient of providing a compartment for the refrigerating coils which is located within the body of the case, produces a case of much simpler design which still has as large a capacity as it would have if the coils were located in a separate compartment. 130

Having described the invention what I claim as new is:

1. A refrigerator display case having a bottom and a rear wall and end walls formed in part from heat insulating material, the top and front side being composed mainly of glass, the inner surface of the bottom and the rear wall having a metal lining, the rear portion of the bottom and the lower portion of the rear wall forming respectively the bottom and one side of a chamber of which the top and other side are formed from a metal sheet whose edges are connected with the metal lining of the bottom and the rear wall whereby an elongated compartment is formed for the reception of the cooling coils and whereby two separate supporting surfaces are formed on different levels, the rear surface being higher than the front surface.
2. A refrigerator display case having the rear wall, the bottom and a portion of the ends formed from opaque material and the top and front side made in part of glass, the rear wall and the bottom having a metal lining, the lower portion of the lining of the rear wall and the rear portion of the lining of the bottom forming two sides of a compartment that extends the entire length of the casing, the other two sides of the compartment being formed from a sheet of metal having angularly related sides, the upper side being parallel with the bottom and having its edge secured to the lining of the rear wall, the other side being secured to the lining of the bottom, whereby two supporting surfaces are formed, the rear supporting surface being higher than the front supporting surface.
3. A refrigerator display case having a bottom and a rear wall formed from opaque heat insulating material, the rear wall and bottom having a sheet metal lining, a metal sheet bent in the direction of its length into two angularly related parts, the edge of one of the parts being connected with the bottom and the edge of the other part being connected with the lining of the vertical wall whereby a chamber is formed for the reception of the refrigerating coils and whereby two vertically spaced display surfaces are formed.
4. A refrigerator display case having a cross section comprising a flat bottom which is formed in part of heat insulating material and a rear wall which extends vertically along the rear edge of the bottom, a stile at the front edge of the bottom and projecting upwardly above the upper surface of the bottom, an upwardly and forwardly inclined wall extending from the upper end of the rear wall to a point about half the distance from the front to the rear, a flat glass top extending from the front edge of the upwardly and forwardly inclined top member and a front glass wall extending from the top of the stile to the forward edge of the

flat glass top, the inner surface of the rear wall and of the bottom having a metal lining, the lower portion of the rear wall and the rear portion of the bottom forming two sides of a refrigerating chamber whose other two walls are formed from a sheet metal plate bent into two angularly related parts whose free edges are secured one to the lining of the bottom and the other to the lining of the rear wall.

In testimony whereof I affix my signature.

CHARLES B. LONGSTRETH.
